THREAD RELEASES FOR SEWING MACHINES

Frederick F. Zeier, Stratfield, Conn., assignor to The Singer Manufacturing Company, Elizabeth, N. J., a corporation of New Jersey

Application January 18, 1952, Serial No. 267,129

9 Claims. (Cl. 112—254)

This invention relates to sewing machine thread controlling devices and more particularly to an arrangement for at will minimizing the frictional drag imposed by the thread controlling devices on the sewing thread.

At the completion of a stitched seam and in the absence of special thread severing and holding devices, the subsequent removal of the work from the machine requires that a surplus of thread be drawn from the supply. This surplus thread must be drawn through thread manipulating instrumentalities such as thread tensions and thread controlling devices which are adjusted in a set position favorable to the delivery of thread during the normal stitching operation, but which impose excessive frictional drag when a greater than normal length of thread is required. Thread breakage during removal of the work, which is frequently the result of this excessive frictional thread drag, requires tedious and time consuming rethreading of the machine.

It is an object of this invention to provide a mechanism which is effective when the presser-foot is lifted for insertion and removal of the work, to shift certain of the thread manipulating instrumentalities such as the thread take-up elements to a relative position more favorable to free passage of thread therethrough.

It is also an object to provide a mechanism of the above character which is effective to shift or open the thread tension elements to release the frictional drag exerted upon the thread by these devices.

With these and other objects and advantages in view as will hereinafter appear, the invention comprises the devices, combinations and arrangement of parts described in the following specification and shown in the accompanying drawings, in which:

Fig. 1 is a front elevational view of a sewing machine, illustrating parts of the presser-foot lifting mechanism and one form of my invention as disposed in operative position suitable for sewing,

Fig. 2 represents an enlarged front elevational view of a portion of Fig. 1, showing the lower thread manipulating devices in inoperative or thread-released position,

Fig. 3 represents a top plan view of the thread manipulating devices of Fig. 2 with the sewing machine frame illustrated in cross section and with all but one of the thread tensioning devices removed to show the parts more clearly,

Fig. 4 represents an end elevational view of the sewing machine of Fig. 1 and,

Fig. 5 represents an enlarged section taken substantially along line 5—5 of Fig. 1, illustrating the details of construction of the thread tension release,

Fig. 6 is a front elevational view of a sewing machine bed having a modified form of my invention applied thereto,

Fig. 7 represents a section taken substantially along line 7—7 of Fig. 6, illustrating the details of construction of the thread tension release of Fig. 6, and

Fig. 8 is a fragmentary top view of the mechanism

2

of Fig. 6 for releasing the thread tension, with the sewing machine frame illustrated in cross section.

In the drawings, the invention is illustrated as applied to a two-thread chain-stitch sewing machine. The sewing machine frame includes a bed 10, from which rises a vertical standard 11 supporting a bracket-arm 12 which overhangs the bed. A rotary drive-shaft 11' is journaled horizontally in the bracket-arm and is provided with connections of the usual type (not shown) for imparting endwise reciprocatory movements to a needle bar 13 which is slidably journaled in a vibratory needle-bar-frame housed in the bracket-arm, the needle-bar carrying a needle 14 at its lower extremity. A bed-shaft 15 is driven from the drive-shaft 11' by means of a belt 16. Supported in the bed and driven from the bed-shaft are the usual lower stitch-forming and feeding instrumentalities including a thread-carrying looper 17, a feed-dog 18, a loop spreader 19, and a movable thread-controlling arm 21. These instrumentalities are similar in details of construction to those disclosed in my prior U. S. Patent No. 2,482,079, September 13, 1949.

Closely associated with the instant invention is the looper-thread controller including the movable thread controlling arm 21 of which the free ends extends through a clearance aperture 22 in the front portion of the bed and cooperates with a normally stationary thread guiding member 23 to engage and control the flow of thread to the looper. As described in detail in another of my prior U. S. patents, No. 2,327,838, August 24, 1943, vibratory movements are imparted to the movable arm 21 in a vertical plane by means of an operative connection with the bed shaft 15.

Secured to the upper surfaces of the bed are work supporting plates 25 and 26; plate 25 being recessed to accommodate a throat-plate 27. An alternating presser mechanism including a presser-foot 28 and an upper feeding foot 29 is operatively supported in the overhanging bracket-arm 12 and spring biased toward the throat-plate 27 and the lower feed-dog 18. The presser mechanism illustrated in the accompanying drawings forms the subject of my copending patent application Serial No. 259,260, filed November 30, 1951 and need not be described in detail herein, except as pertains to the means which is provided for at will raising both the presser-foot and the feeding foot; this means being utilized to actuate a mechanism for minimizing the frictional drag exerted on the sewing threads. This presser-lifting means includes a bell-crank lever 31 pivoted to the bracket-arm. One arm 32 of the lever 31 is connected, as by a chain 34, to any suitable foot treadle or knee-shift (not shown). A rod 35 pivoted at one end to arm 33 of the bell-crank lever 31, is secured at its other end to a rock arm 36 which controls the movement of the cam 37 which serves to raise and lower the presser mechanism in a manner described in detail in my above mentioned pending application.

The accompanying drawings, in the interest of clarity, illustrate only one needle and one looper. It is manifest, however, that a plurality of needles and loopers may be employed to effect seams having a corresponding number of laterally spaced lines of stitching. The friction relieving devices of this invention, moreover, are readily adapted to accommodate any desired number of looper threads as will be apparent from the following description. As shown in Fig. 1, each looper thread, of which one designated T is illustrated, is directed from a supply (not shown) located above and to the rear of the sewing machine downwardly through a vertical thread guiding tube 39 secured on the standard. The thread is then passed through a stationary thread guide 40 to a tensioning device indicated generally as 41 which in the present embodiment is of the type including a pair of opposed

tensioning disks 42—42 arranged on a stud 43 which is threaded to accommodate a thumb nut 44 adapted adjustably to confine a coil spring 45 which presses the tension disks together with the required pressure. From the tensioning device, the looper thread is directed to a thread controller which comprises a normally stationary thread guiding member 23 having a shank portion 50 and an end portion 51 bent into parallel spaced relation with the shank. Aligned thread guiding apertures 52—52 are formed in the shank 50 and end portion 51, thus defining a definite path for the thread as it passes through the controlling device. The previously described movable thread controlling arm 21 is arranged to move in a vertical path between the shank and end portions of the normally stationary guide member thereby to engage the thread and periodically form a loop or bight therein. The free extremity of the movable thread engaging member 21 is, in addition, bent to form a hook 53 which is arranged so that the free extremity of the hook is disposed to engage the thread between the normally stationary control member and the tension device thereby adding to the effectiveness of the thread controller. The function of the thread controlling device, it is pointed out, may be varied by changing the position of the normally stationary guide or by changing the timing of the movable arm with respect to the looper by altering the timing of the thread controller driving connection with the bed shaft. According to these adjustments the thread controller may function either as a take-up, a stitch-by-stitch pull off, a control device for determining the elasticity of the resulting seam, or a combination of these functions. The thread is directed from the thread controlling device to the looper 17 by means of thread guides 54 and 55 secured to the bed.

As best illustrated in Figs. 1 and 4, a needle thread tension device, indicated generally as 61, is secured to the bracket-arm 12. The tension device 61 is of the well known opposed disk type similar to that of the looper thread tension device described above, and it includes opposed tension disks 62—62 arranged on a threaded stud 63 which is provided with a thumb nut 64 adapted adjustably to confine a coil spring 65 in position to bias the tensioning disks together. The tension device 61 also is provided with a release pin 66 which is slidably journaled in the stud 63. The stud 63 is slotted, as at 67, and provided with a collar 68 arranged between the tension disks 62—62 and the coil spring 65. The collar 68, in a manner well known in the art, is formed with a diametrically arranged web (not shown) disposed in the slot 67 and by which the force of the spring 65 pressing the tension disks 62—62 together may be released in response to movements imparted to the pin 66. In order to affect this tension-relieving movement of pin 66, a curved cam-member 59 is secured to arm 33 of the presser-lifting crank lever 31. The cam-member is arranged to contact the push rod 60 which is journaled transversely in the bracket-arm 11 so as to contact the release pin 66.

In the present invention, the normally stationary thread-guiding member 23 of the looper thread controller is secured to a boss 70 formed at the extremity of one arm 71 of a bell-crank lever 72 which is secured by means of the pivotal connection 73 to the front wall of the machine bed 10. In Fig. 1, the bell-crank lever 72 is illustrated in sewing position in which the thread guide 23 is operatively disposed in a position in which the movable thread-engaging arm 21 engages the thread T and in its downward movement draws out sufficient thread to properly influence the seam characteristics at the stitching point as described above. The sewing machine is provided with an actuating linkage which is connected at one end to the presser lifting lever 31 and at its other end to a second arm 74 of the bell-crank lever 72 such that when the presser-lifting lever is depressed, the bell-crank lever 72 is turned in a counterclockwise direction as viewed in Fig. 1, thus shifting the thread guide 23 to

a lowered position as illustrated in Fig. 2. In this lowered position of the thread guide 23, the path of the thread through the thread controller is straightened to more closely approximate a straight line regardless of the position of the movable thread-engaging arm 21, and thus the frictional drag on the thread due to the normally devious path through the thread controller is minimized. For purposes of comparison in both Fig. 1 and Fig. 2, the movable thread controller is illustrated in the same point in the cycle of movement.

The linkage connection between the bell-crank lever 72 and the presser lifting lever 31 comprises a two-part push-rod of which the upper part 80 is pivoted to the presser-lifting lever 31 and the lower part 81 is pivoted to a transversely arranged lever 82 which is pivoted at 83 to the bed and maintained in proper position on the bed by a slotted guide bar 84. The parts of the push-rod are slidably joined by means of spaced slide collars 85—85, the upper collar being secured to the upper part 80 of the push-rod while the lower collar is secured to the lower part 81 of the push-rod. A coil spring 86 is arranged on one part of the push-rod between the slide collars 85—85 so that the motion imparted to the thread controller is a gradual yielding one and no binding of parts or breakage can occur should the movement of the presser-lifting lever exceed that desired for the maximum shifting of the thread controller. A stop-collar 87 is secured to the upper part 80 of the push rod so as to insure positive positioning of the actuating linkage in normal operative position when the presser-foot is lowered. Pivotedly secured to the front wall of the machine bed 10 is an intermediate bell-crank lever 90, of which one arm 91 is bifurcated to accommodate the transverse lever 82. A second arm 92 of the intermediate bell-crank lever 90 is arranged substantially parallel with the second arm 74 of bell-crank lever 72, and the extremities of these arms 92 and 74 are connected by means of a link 93.

As the presser-foot lifting lever is turned and the needle-thread tensioning device and looper-thread controller are shifted to positions in which these devices exert a minimum of frictional drag on the thread as described above, provision is made in the present invention for simultaneously shifting the looper thread tensioning devices to an inoperative or open position in which a minimum of frictional drag is imposed on the looper thread. Figs. 1 through 5 illustrate one preferred form of construction and arrangement of parts by which this simultaneous friction release on the looper thread is attained. In this embodiment, the tension devices, indicated generally as 41, and the thread guides 40, one for each tension device, are secured to a supporting bar 101. As best illustrated in Fig. 5, the bar 101 is formed with countersunk apertures 102 to accommodate the tension studs 43 in place on the bar. The supporting bar 101 is secured to the sewing machine bed 10 by fastening screws 104—104 and by means of spacing collars 105—105 which serve to position the bar 101 in spaced relation to the bed in order to provide clearance for the actuating link 93. Each of the spacing collars 105 is formed adjacent the supporting bar 101 with a portion of reduced diameter which provides a shoulder 106 opposite the supporting bar 101. As best shown in Fig. 2, a slide-plate 107 is formed with elongated apertures 108—108 each of which accommodates the reduced portion of one of the spacing collars 105—105. The slide-plate is thus slidably confined against the supporting bar 101 by the shoulders 106 of the spacing collars. Secured to the slide-plate adjacent each thread tension device 41 is a U-shaped bent wire tension-opening member 110 which is arranged to straddle the tension supporting bar 101. Fixed to the slide-plate 107 is a driving pin 112 which is embraced by the bifurcated extremity of a third arm 113 formed on the bell-crank lever 72.

Figs. 1 and 4 illustrate the relative position of parts 75 when the presser-foot is lowered as during the sewing

operation of the machine. In this position, the arm 32 of the presser-lifting lever 31 is raised and the cam 59 is turned to release the push rod 60 which permits the needle-thread tension device 61 to assume an operative position.

The stop collar 87 which is secured to rod 80 engages the collar 85 of the rod 81 to move the lever 82 to the position shown in Fig. 4 in a positive manner. In this position, both the intermediate bell-crank 90 and the three-armed lever 72 are turned in a clockwise direction to the greatest extent possible and, consequently, the normally stationary thread guide 23 of the thread controller is raised to operative position and the slide plate 102 is shifted to a position in which the wire tension-opening members 110 disengage the tension disks.

When the arm 32 of the presser-foot lifting lever is depressed to lift the presser-foot, the cam 59 serves to shift the push rod 60 to relieve the pressure of the spring 65 from the needle-thread tension disks 62—62. By means of the collars 85—85 and the spring 86, the rod 81 is gradually depressed and through the lever 82, the intermediate bell-crank 90 and the connecting link 93, the three-armed lever 72 is turned in a counterclockwise direction. The normally stationary thread guiding member 23 of the thread controller is depressed to straighten the thread path, and the slide-plate and tension opening wires are moved so as to force the tension disks apart as shown in Figs. 2 and 3.

Figs. 6, 7 and 8 illustrate a modified form of my invention which is especially suitable in a machine which has a larger number of needles and consequently a larger number of looper threads. Principally, the differences in construction between this modified form and the above discussed embodiment occur with respect to the looper thread tension devices and the means for relieving the frictional drag imposed thereby.

In the modified form, tension devices indicated generally as 120, together with stationary thread guides 121, are secured on a supporting plate 122. The supporting plate is formed with tangs 123—123 by which it is secured to the machine bed 10 with the aid of fastening screws 124—124, and is spaced from the bed 10 by spacing collars 125—125. Each tension device 120 comprises a stud 126 and a pair of opposed tension disks 127—127 biased together by means of a coil spring 128 which is maintained on the stud by a thumb nut 129. The tension device 120 is similar to the needle thread tension device 61 described above in that there is provided a tension release pin 130 slidably journaled in the stud 126. A collar 131 is arranged between the tension disks and the coil spring and provided with a diametrically arranged web 132 disposed in a slot 133 formed in the supporting stud 126. The release pin 130 is adapted to engage the web 132 and thereby compress the spring 128 to relieve the frictional drag which is normally imposed on the thread. In order that the looper thread tension may be released simultaneously with the raising of the presser-foot, the tension supporting plate 122 is provided at each side with a pair of spaced hinge knuckles 134—134. Similar hinge knuckles 135—135 are formed to extend from the tension release plates 136 and 137; the knuckles 134 and 135 being pivotally secured together by means of hinge pins 138—138.

One of the tension release plates 137 is provided with coil-spring connections with the machine frame, each connection including a fastening screw 139 threaded into the release plate and a similar fastening screw threaded into the machine frame. Secured between the fastening screws 139—139 is a coil spring 140 which serves to bias the release plate out of operative contact with the tension release pin 130. The other tension release plate 136 is provided with a cam-follower projection 141 which is arranged in the path of a cam surface 142 formed on a block 143 which is secured by slot and screw connections 144 for limited adjustment on a connecting link 145 be-

tween the intermediate bell crank 90 and the three-armed lever 72. This connecting link 145 is offset at 146 so as not to interfere with the fastening screws 124—124 and is adapted to enter and to be guided by radial slots 147 in the spacing collars 125. The release plate 136 is provided with extension disks 150—150 secured near the free edge of the plate and arranged to extend beyond the edge of release plate 136 so as to contact and interconnect the plates 136 and 137 for movement together in response to the spring 140 in one direction, and in response to cam actuated movements in the other direction.

In the drawings, the parts of the modified form are illustrated in operative position suitable for sewing with the presser-foot lowered. As the presser-foot is raised it will be appreciated that connecting link 145 will be moved toward the right as viewed in Figs. 6 and 8. The cam surface 142 will turn the tension release plate 136 about the hinge pin 138 and by virtue of the interconnecting extension disks 150—150, the cam actuated movement of plate 136 is imparted to release plate 137 so that the plates 136 and 137 simultaneously bear against the tension release pin 130 to release the frictional drag on the looper threads.

Having thus set forth the nature of the invention, what I claim herein is:

1. In a sewing machine a presser-foot and a presser-foot lifting mechanism, a thread controlling device including a thread engaging member, driving connections between said sewing machine and said thread engaging member imparting a predetermined range of movement to said member, and a complementary normally stationary thread guiding member, spaced thread embracing guides carried by said thread guiding member, said guides being normally disposed on opposite sides of said thread engaging member to direct the thread into the range of movement of said thread engaging member, and means for shifting said stationary thread guiding member beyond the range of movement of said thread engaging member comprising a linkage carried by said sewing machine and connecting said presser-foot lifting mechanism with said thread guiding member.

2. In a sewing machine having a presser-foot and a presser-foot lifting mechanism, a thread-controlling device including a normally stationary thread guiding member and a thread engaging member complementary to each other, said thread guiding member having spaced thread controlling surfaces, said thread engaging member driven in timed relation with said sewing machine between two extreme positions on a path extending between said thread controlling surfaces to effect a sinuous thread path of varying amplitude, a linkage connecting said normally stationary thread guiding member with said presser-foot lifting mechanism, said linkage being operative when said presser foot is lifted to shift said normally stationary thread controlling surfaces beyond one extreme position of said thread engaging member to effect a reduction of the amplitude of said sinuous thread path.

3. In a sewing machine having thread manipulating instrumentalities including a spring-loaded thread tension device and a thread controller having a normally stationary thread guiding component, and a thread engaging member driven from said sewing machine so as to effect a sinuous thread-path of varying amplitude, means for reducing the frictional drag imposed by said instrumentalities on the thread comprising, a tension release member shiftable to a position in which said member assumes the spring-load of said tensioning device, an actuating linkage for said tension release carried by said sewing machine, and a supporting member for the normally stationary thread guiding component of said thread controller, said supporting member being operatively connected with said actuating linkage for movement to a position in which the amplitude of the sinuous thread-

path is reduced in unison with the spring-load accommodating movement of said tension release member.

4. In a sewing machine having stitch-forming instrumentalities, a presser mechanism, and a presser-lifting mechanism carried by said sewing machine, a thread-controlling device including a three-armed bell-crank lever pivoted to said sewing machine, a normally stationary thread-guiding member secured to a first arm of the bell-crank lever, said thread-guiding member having spaced thread-guiding apertures, a thread-engaging element movable in a path between said thread-guiding apertures, an actuating linkage connected at one end to said presser-lifting mechanism and at the other end to a second arm of said bell-crank lever, one or more thread tension devices secured to said sewing machine, a tension-release plate endwise slidably supported for movement relative to said thread tension device, and an operative connection between said tension-release plate and a third arm of said bell-crank lever.

5. In a sewing machine having stitch forming instrumentalities, a presser mechanism, and a presser-lifting mechanism carried by said sewing machine, a thread-controlling device including a normally stationary thread-guiding member and a movable thread-engaging member, an actuating linkage operatively connected at one end to said presser-lifting mechanism and at the other end to said normally stationary thread-guiding member to shift said thread-guiding member to a position more favorable to free passage of thread therethrough when said presser-foot is lifted, a thread tension device comprising a support bracket secured to the sewing machine, one or more pairs of opposed tension disks supported on said bracket, a tension-release plate hinged to said bracket, and an operative connection intermediate the ends of said actuating linkage with said tension-release plate.

6. In a sewing machine having a presser-foot, a presser-foot lifting mechanism and thread manipulating instrumentalities including a spring loaded thread tension device and a thread controller having a normally stationary thread guiding component and a movable thread engaging member, means for reducing the frictional drag imposed by said instrumentalities comprising a tension release plate shiftable to assume the spring load of said tension device, a support for said normally stationary thread guiding component, said support shiftable to position said component beyond effective range of said movable thread engaging member, an actuating linkage, means connecting said actuating linkage to said presser lifting mechanism and to both said tension release plate and said support member to shift said parts simultaneously into tension releasing position in response to presser lifting movement, said linkage including a connection having interengaging surfaces arranged to effect a positive repositioning of said thread manipulating devices into operative position when said presser foot is lowered and a spring arranged to yieldingly transmit said frictional drag releasing movements.

7. In a sewing machine having stitch-forming instru-

mentalities, a presser mechanism and a presser lifting mechanism, a thread-controlling device including a thread-engaging member driven in a predetermined closed path in timed relationship with said stitch-forming instrumentalities and a thread-guiding member having spaced thread-guiding apertures disposed in cooperative relation with said thread-engaging member, said thread-guiding member supported on said sewing machine for movement between a first position in which said spaced thread-guiding apertures are disposed one at each side of the path of motion of said thread-engaging member and a second position in which both of said apertures are disposed at one side of the path of motion of said thread-engaging member, and a linkage connected at one end to said presser lifting mechanism and at the other end to said thread-guiding member, said linkage arranged to shift said thread-engaging member into said second position when said presser-foot is lifted and into said first position when said presser-foot is lowered.

8. A thread-controller for a sewing machine comprising, a thread-engaging member driven in a predetermined closed path and a thread-guiding member having spaced thread-guiding apertures associated therewith, said thread-guiding member supported on said sewing machine for movement between a first position in which said spaced thread-guiding apertures are disposed one at each side of the path of motion of said thread-engaging member, and a second position in which both of said apertures are disposed at one side of the path of motion of said thread-engaging member, and a manually operable linkage connected at one end to said thread-guiding member, said linkage arranged to shift said thread-guiding member into either said first or said second position at the will of the sewing machine operator.

9. Thread manipulating instrumentalities for a sewing machine comprising a thread tension device having a spring loaded operative position, a thread tension release member shiftable to assume said spring load, and a thread controller comprising spaced thread guides, a movable thread guide supporting member, and a thread-engaging arm reciprocable in a path between said thread guides, means shifting said tension release member to assume said thread tension spring load and simultaneously shifting said thread guides with respect to the path of said reciprocable thread-engaging member, said means comprising a manually operated linkage connected to said thread guide supporting member, and an operative interconnection between said thread guide supporting member and said thread release member to synchronize the shifting of said members.
